United States Patent Office

Des. 221,207
Patented July 20, 1971

221,207

SCREEN SASH HANDLE UNIT

Henry L. Majeske, Goshen, Ind., assignor to Homeshield
Industries Inc., Elmhurst, Ill.

Filed May 19, 1969, Ser. No. 17,209

Term of patent 14 years

Int. Cl. D8—03

U.S. Cl. D8—150

FIG.1

FIG.4

FIG.2

FIG.3

FIG.5

FIG.6

FIG. 1 is a front view of a screen sash handle unit showing my present design.

FIG. 2 is an enlarged front elevational view thereof.

FIG. 3 is an enlarged rear elevational view thereof.

FIG. 4 is an end elevational view taken from the right hand side of the article as shown in FIG. 2.

FIG. 5 is a top plan view thereof.

FIG. 6 is a sectional view taken on the line 6—6 of FIG. 2.

The broken lines in the drawings are for illustrative purposes only.

I claim:

The ornamental design for a screen sash handle unit, as shown and described.
